UNITED STATES PATENT OFFICE.

RONALD B. JESTER, OF NEW CUMBERLAND, WEST VIRGINIA, ASSIGNOR TO HARRY A. SCHNELBACH, OF FOLLANSBEE, WEST VIRGINIA.

LIFTING-JACK.

1,307,360.

Specification of Letters Patent. Patented June 24, 1919.

Application filed January 11, 1918, Serial No. 211,331. Renewed November 21, 1918. Serial No. 263,634.

To all whom it may concern:

Be it known that I, RONALD B. JESTER, a citizen of the United States, and a resident of New Cumberland, in the county of Hancock and State of West Virginia, have invented a new and useful Improvement in Lifting-Jacks; and I do hereby declare the following to be a full, clear, and exact description thereof.

10 My invention relates to lifting-jacks.

The object of my invention is to provide a jack of this character which is very strong and durable in construction, and which has the novel feature of automatically reversing the lifting-bar so that it will be lowered after the said lifting-bar has been raised to its full height.

To these ends my invention comprises the novel features hereinafter set forth and claimed.

In the accompanying drawings, Figure 1 is a side elevation of my improved jack; Fig. 2 is a vertical sectional view taken at right angles to Fig. 1; Fig. 3 is a cross-section on the line 3—3 of Fig. 2, Fig. 4 is a vertical section showing the parts in position for lifting the lifting-bar; Fig. 5 is a like view showing the parts in position for lowering the lifting-bar; Fig. 6 is a like view showing a slightly different position of the parts from Fig. 5; Figs. 7 and 8 are details of the retaining-pawl; Fig. 9 is a section on the line 9—9, Fig. 4; and Fig. 10 is a perspective view of the lifting and lowering pawl.

35 In the drawings, the numeral 2 designates a suitable base or support which carries the frame or casing 3 inclosing the operating parts. Arranged to move vertically up and down within the casing 3 is the lifting-bar 4, which has the oppositely-disposed teeth 5 and 6 with the depression or recess 7 formed between the same. Located in this recess 7 and carried by the lifting-bar is the guide 8 which has the teeth 9 on one side thereof, the other side 10 being plain.

On the rear of the lifting-bar 4 are the teeth 11 which are engaged by the holding-pawl 12 which extends across the lifting-bar, said pawl being pivoted by the pins 13 to the casing 3. A spring 14 is carried by the pawl, and the free end of said spring bears against the casing 3 whereby said pawl is normally held in engagement with the teeth 11. The

holding-pawl 12 is provided with the tripping-arm 15 for the purpose fully herein- 55 after set forth.

The lifting and lowering-pawl 16 is mounted at its lower end on the operating-shaft 17, said pawl being cutaway at its lower end as at 18, to permit its being 60 slipped over the crank-arm 19 of the shaft 17. The crank-shaft 17 projects entirely through the casing, being mounted in bearings 20 and 20^a. The outer end of said crank-shaft has the seat 21 for a ratchet- 65 arm, or a crank-arm for rotating said crank-shaft. It will be apparent from the above that upon the turning of the crank-shaft 17, the pawl 16 will be raised and lowered. The pawl 16 is provided at its upper end on its 70 inner face with the triangular-shaped lug 22 from which the stud 23 projects inwardly. The stud is movable longitudinally in the lug to permit withdrawal from guiding engagement with the guide 8 when it is desired to 75 shift the operating pawl from elevating to lowering position for any position of the lifting bar. The stud preferably is in the form of a plunger mounted in the bore 22^a of lug 22, and held in operative position by the 80 spring 23^a, the opposite end of the plunger being provided with a finger button by which the plunger may be retracted. The triangular lug 22 is adapted to engage the oppositely-arranged teeth 5 and 6 of the 85 lifting-bar in the raising and lowering of same, as will more fully hereinafter appear.

The stud 23 is arranged to lie on either side of the guide 8, said stud being located on the straight side 10 of the guide 8 in the 90 operation of lifting the lifting-bar, and on the toothed side 9 on the lowering of the lifting-bar.

A spring 24 is secured to the pawl 16 at 25, and the free end of said spring bears 95 against the inner wall of the casing 3, said spring acting normally to force the pawl 16 toward the right, as indicated in Fig. 4.

The pawl 16 is provided with the tripping-lug 26, which is adapted to engage the 100 trip-arm 15 in the lowering of the jack, as indicated in Fig. 6, and as will more fully appear in the description of the operation of the jack.

A spring-finger 27 is located at the lower 105 end of the guide 8, said finger being secured

in the lifting bar by the screw 28. This spring is in the path of the stud 23 of the pawl 16, and acts to move said pawl over to the left, as indicated in Figs. 5 and 6, where-
5 by the stud 23 works in and out of the teeth 9 of the guide in the lowering of the lifting-
bar, as will fully hereinafter appear.

The removable bearing plate 20^a closes the opening in the casing 3 at the point where
10 the shaft 17 extends through said casing so that by the removal of said plate, access may be had to the interior of the casing for purposes of inspection, repair, etc.

In the operation of my improved jack
15 when the parts are in the position indicated in Fig. 4, and it is desired to raise the lifting-bar 4, the operator by rotating the crank-shaft 17, either by an ordinary ratchet-arm or by a crank applied to the
20 seat 21, imparts a reciprocating movement to the pawl 16, which, as indicated in Fig. 4, is located with the stud 23 on the plain side of the guide 8. As the pawl 16 is lifted, it will engage in succession the teeth 5 on the
25 right-hand side of the lifting-bar, and on each upward movement of said lifting-pawl the lifting-bar will be lifted, while upon the lowering of the lifting-pawl, which is permitted to move to the left by compressing
30 the spring 24, the holding-pawl will act to hold the lifting-bar in its raised position until the pawl has been lowered and engaged by another tooth preparatory to lifting again. In this manner, by step by step
35 movement, the lifting-bar is raised, and when the stud 23 meets the spring 27, said spring will act to guide the stud together with the pawl over to the left, whereupon said stud is in position to engage the teeth
40 or cams 9 on that side of the guide 8. The operator still continues to work the operating handle in the same manner as in lifting the jack, and it will be apparent from Figs. 5 and 6 that stud 23 moving up along the
45 cam faces of the teeth 8 will act to move the upper end of the lifting-pawl 16 into engagement with the teeth 6 of the lifting-bar on the left of said bar upon the upward movement of the pawl, and as said pawl 16
50 is lowered, said pawl will carry the weight, and, at the same time, the tripping-lug 26 engages the tripping-arm 15 and moves said arm outwardly, whereby the holding-pawl 12 is disengaged from the teeth 11 and the
55 lifting-bar is permitted to descend by a step by step movement, just in the same manner as the bar was lifted.

When the lifting-bar has been lowered in this manner to its lowermost position, the
60 stud 23 will pass over the top of the guide 8, the pawl 16 being shifted automatically by the spring 24 over into position for lifting again.

What I claim is:

65 1. In a lifting-jack, the combination with

a suitable frame, of a lifting-bar associated therewith, a pawl for holding the bar in its various positions, a pawl for lifting and lowering the bar, means for raising and lowering the last mentioned pawl, and means 70 for automatically shifting the last mentioned pawl to reversing position, said last mentioned pawl being subsequently operable to raise and lower the lifting-bar.

2. In a lifting-jack, the combination with 75 a suitable frame, of a lifting-bar having oppositely disposed teeth, a holding-pawl, a lifting and lowering-pawl arranged between said teeth, means for raising and lowering said last-named pawl, and means for shift- 80 ing said last-named pawl to engage one or other set of said teeth.

3. In a lifting-jack, the combination with 85 a suitable frame, of a lifting-bar having oppositely-disposed teeth, a holding-pawl, a lifting and lowering-pawl arranged between said teeth, means for raising and lowering said last-named pawl, and means for automatically shifting said last-named pawl to engage one or other set of said teeth. 90

4. In a lifting-jack, the combination with 95 a suitable frame, of a lifting-bar having oppositely-disposed teeth, a holding-pawl, a pivotally-mounted lifting and lowering-pawl arranged between said teeth, means for raising and lowering said last-named pawl, and means for shifting said last-named pawl to engage one or other set of said teeth.

5. In a lifting-jack, the combination with 100 a suitable frame, of a lifting-bar having oppositely-disposed teeth, a holding-pawl, a lifting and lowering pawl, means for raising and lowering said pawl, a guide on said lifting-bar between said oppositely-disposed teeth having cams on one side thereof, a projection on said last-named pawl lying on one side of said guide, and means for shifting said pawl to move said projection from one side to the other of said guide. 105

6. In a lifting-jack, the combination with 110 a suitable frame, of a lifting-bar having oppositely-disposed teeth, a holding-pawl, a lifting and lowering pawl, means for raising and lowering same, a guide on said lifting-bar between said oppositely-disposed 115 teeth having cams on one side thereof, a projection on said last-named pawl lying on one side of said guide, and means for automatically shifting said pawl to throw said projection from one side to the other of said 120 guide.

7. In a lifting-jack, the combination with 125 a suitable frame, of a lifting-bar having oppositely-disposed teeth, a holding-pawl, a pivotally-mounted lifting and lowering pawl lying between said oppositely-disposed teeth, means for raising and lowering said pawl, a guide on said lifting-bar between said oppositely-disposed teeth having cams on one side thereof, a projection on said last- 130

named pawl adapted to engage the teeth on said guide, and means carried by said lifting-pawl for engaging said holding-pawl whereby said holding-pawl is moved out of 5 position when said lifting-pawl is lowered.

8. In a lifting-pawl, the combination with a suitable frame, of a lifting-bar having oppositely-disposed teeth, a holding-pawl, a lifting and lowering-pawl, means for raising 10 and lowering said pawl, a guide on said lifting-bar between said oppositely-disposed teeth having cams on one side thereof, a projection on said last-named pawl lying on one side of said guide, a spring engaging said 15 lifting-pawl, and means for shifting said pawl to throw said projection from one side to the other of said guide.

9. In a lifting-jack, the combination with a suitable frame, of a lifting-bar having oppositely-disposed teeth, a holding-pawl, said lifting-bar having teeth on its back face engaged by said holding-pawl, a tripping-finger on said holding-pawl, a lifting and lowering-pawl, means for raising and lowering 25 same, a guide on said lifting-bar between said oppositely-disposed teeth having cams on one side thereof, a projection on said last-named pawl adapted to engage the cams of said guide, and a projection on said lifting- 30 pawl in the path of said tripping-finger whereby said holding-pawl is disengaged

from its teeth on the lowering of said lifting-pawl.

10. In a lifting jack, the combination with a suitable frame, of a lifting-bar having oppositely-disposed teeth, a holding pawl, a lifting and lowering pawl, means for raising and lowering said pawl, a guide on said lifting-bar between said oppositely-disposed teeth having teeth on one side thereof, and a 35 withdrawable projection on said last-named pawl lying on one side of said guide, whereby said projection may be shifted to one side or the other of said guide intermediate of the maximum movement of said 40 lifting bar.

11. In a lifting-jack, the combination with a suitable frame, of a lifting-bar having oppositely-disposed teeth, a lifting and lowering pawl arranged between said teeth, means 50 for raising and lowering said pawl, means for shifting said pawl to engage one or other set of said teeth, and a spring-actuated holding-pawl on said frame engaging teeth formed on the rear of said lifting-bar. 55

In testimony whereof, I, the said RONALD B. JESTER, have hereunto set my hand.

RONALD B. JESTER.
